Primary Examiner — John Windmuller*Assistant Examiner* — Benjamin M Weeks(74) *Attorney, Agent, or Firm* — Greenberg Traurig, LLP(57) **CLAIM**

We claim the ornamental design for a broadcast spreader, as shown and described.

DESCRIPTION

FIG. 1 is a perspective view of our broadcast spreader; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines represent portions of the broadcast spreader that form no part of the claimed design.
